CLAIM

We claim the ornamental design for a fender skirt, as shown and described.

DESCRIPTION

FIG. 1 is a perspective view of a fender skirt for a front wheel opening of a vehicle in accordance with our new design.

FIG. 2 is an enlarged perspective view of the fender skirt shown in FIG. 1;

FIG. 3 is a front view of the fender skirt shown in FIG. 2;
FIG. 4 is an end view of the fender skirt shown in FIG. 2;
FIG. 5 is an opposite end view of the fender skirt shown in FIG. 2;

FIG. 6 is a top view of the fender skirt shown in FIG. 2; and,
FIG. 7 is a bottom view of the fender skirt shown in FIG. 2.
The broken lines showing portions of the associated vehicle
and mounting flanges of the fender skirt are for illustrative
purposes only and form no part of the claimed design.

The back sides of the fender skirt are unornamented and are
thus not shown in the drawing figures.

FIGS. 1-7 illustrate our novel design for the front left-side
fender skirt. The applicant also claims the front right-side
fender skirt, which is a mirror image and therefore not
separately illustrated.
